(Cl. D48—23)

*Fig. 1.Fig. 2.Fig. 3.Fig. 4.Fig. 5.Fig. 6.*FIG. 1 is a perspective view of a fluorescent lighting fixture showing our new design;

FIG. 2 is a perspective view of the lighting fixture of FIG. 1 but turned out to show the other face thereof;

FIG. 3 is a top plan view of the lighting fixture shown in FIG. 1;

FIG. 4 is a side elevational view of the lighting fixture; the opposite side thereof not shown is a mirror image of the side shown;

FIG. 5 is an end elevation as seen from the left of FIG. 4;

FIG. 6 is also an end elevation as seen from the right of FIG. 4.

This is a continuation of application Ser. No. D.80,141, filed May 25, 1964, and now abandoned.

The dominant features of our design reside in the portions shown in full lines.

We claim:

The ornamental design for an outdoor fluorescent lighting fixture, as shown and described.
